[57] CLAIM

The ornamental design for spacer element for scaffolding, as shown and described.

DESCRIPTION

FIG. 1 is a front perspective view of a spacer element for scaffolding showing my new design;

FIG. 2 is a top plan view of the spacer element in its operative position, the broken line showing of scaffolding parts is for illustrative purposes only and forms no part of the claimed design;

FIG. 3 is a side elevational view thereof;

FIG. 4 is a top plan view of a second embodiment of a spacer element for scaffolding showing my new design; and,

FIG. 5 is a top plan view of a third embodiment of a spacer element for scaffolding showing my new design.

FIG. 1

FIG. 2

FIG. 3

FIG. 4

FIG. 5
